Application filed July 25, 1932. Serial No. 44,439. Term of patent 7 years.

To all whom it may concern:

Be it known that I, KENNETH D. HAUSER, a citizen of the United States, residing at Portland, in the county of Multnomah and State of Oregon, have invented a new, original, and ornamental Design for a Flask, of which the following is a specification, reference being had to the accompanying drawing forming a part thereof.

The drawing is a perspective view of a flask showing my new design. As shown, the de-

sign comprises a flask which is generally oblong in horizontal section. The flask gradually increases in width from the bottom upwardly to a point well above the center of the flask and then slopes inwardly in a gradual curve to the neck thereof.

I claim:

The ornamental design for a flask, as shown and described.

KENNETH D. HAUSER.
